DESIGN FOR AN ELECTRIC LIGHT BOWL

Albert J. D. Ohm, Buffalo, N. Y., assignor to Mar-
kel Electric Products, Inc., Buffalo, N. Y., a
corporation of New York

Application August 17, 1945, Serial No. 121,456

Term of patent 14 years

(Cl. D48—16)

To all whom it may concern:

Be it known that I, Albert J. D. Ohm, a citizen of the United States, residing at Buffalo, in the county of Erie and State of New York, have invented a new, original, and ornamental Design for Electric Light Bowls, of which the following is a specification, reference being had to the accompanying drawing, forming part thereof.

Figure 1 is a view half in side elevation and half in section of an electric light bowl, embodying my new design.

Figure 2 is a partial bottom plan view of the same, it being understood that details of the pattern are repeated throughout the area enclosed within the dot and dash lines in relative positions corresponding to the relative positions in which they are shown.

I claim:

The ornamental design for an electric light bowl, as shown and described.

ALBERT J. D. OHM.
